PRINTING PRESS

Arthur W. Gillman, Berkeley, Calif., assignor of
one-half to John S. Pinney, San Francisco,
Calif.

Application April 27, 1931. Serial No. 533,072

2 Claims. (Cl. 101—348)

This invention relates to improvements in printing presses and more particularly to roller trucks for the inking rolls thereof.

The principal object of the invention is to 5 compensate for variations in the diameters of the inking rolls.

Another object is to limit the application of ink to the type faces only, by preventing excess pressure by oversized rolls.

10 Another object is the independent adjustment of each individual roll relative to its diameter.

A further object is to provide a sturdy easily adjustable traction roller applicable to the conventional form of inking roll shaft.

15 Other objects and advantages will appear as the description progresses.

In this specification and the accompanying drawings the invention is disclosed in its preferred form, but it is to be understood that it is 20 not limited to this form because it may be embodied in other forms. It is also to be understood that in and by the claims following the description it is desired to cover the invention in whatsoever form it may be embodied.

25 In the two sheets of drawings:

Fig. 1 is a fragmentary perspective view from above of the inking mechanism of a conventional platen printing press with this invention applied thereto.

30 Fig. 2 is an enlarged detail in vertical section of the adjustable traction roller and associated parts in the inking assembly.

Fig. 3 is a similar view showing the range of adjustment of the traction roller.

35 Fig. 4 is a transverse vertical section of the traction roller.

In detail the construction illustrated in the drawings comprises the bed of a conventional printing press having the guide tracks 1 thereon. These tracks extend vertically on opposite sides of and a definitely maintained height above 40 the plane of the platen 2. They curve rearwardly at 3 and incline upwardly at 4—4 to opposite sides of the ink disc 5.

45 The ink rolls 6—7—8 are molded on the axial shafts 9—10—11 respectively. These shafts protrude at each end of the rolls and are journaled in the trucks 12—12 and 13 on opposite sides of the bed of the press. The trucks 12 are pivoted at 14 to saddle rods 15, which are guided in the roll frames 16 at each side of the press and under spring tension to draw the rolls 6—7 toward the platen 2 and the ink disc 5, in the usual manner. The roll 8 is similarly controlled 50 by the rod 17 with like results. Where a multi-

plicity of ink rolls are used, as illustrated, it is necessary to separately mount them as shown, to permit them to flexibly pass the turn in the tracks at 3.

The spring tension of the rods 15—17 is taken 60 by the anti-friction traction rollers 18—18 on the shafts 9—10—11. The rolls 6—7—8 pick ink off the disc 5 and deposit it on the faces of the type X, held in the form or chase fixed to the face of the platen 2, with each cycle of operation of 65 the press.

Heretofore it has been the practice to have all the traction rollers 18—18 the same diameter. If the diameters of the rolls 6—7—8 vary the pressure upon the ink disc 5 and the type form 70 will vary accordingly. It is a fact that the nature of the composition of the rolls makes it impossible to mold and maintain a fixed diameter in these rolls. They are subject to diametric expansion and contraction by atmospheric changes. 75 They are also subject to surface mutilation by the type faces, especially by brass rules, etc., if the pressure is too great, due to larger diameters among the rollers 6—7—8.

Obviously the larger rollers will exert a heavier 80 pressure against the ink disc 5 and the type faces X'. Any excess ink forced below the plane of the type face will be transferred to the imprint. The unequal distribution of ink by the larger and smaller rolls makes a good imprint impossible. 85

The above and other disadvantages are entirely eliminated by the use of this invention.

Broadly stated, the invention consists of a concentric traction roller with an eccentrically variable axis. 90

The structure of the invention comprises the annular concentric roller 18, having the concentric center bore 19, see Figs. 2—4. The outer face of the roller tapers inwardly as at 20, and the inner face is countersunk to form the annular 95 flange 21.

The bearing of the roller comprises the sleeve 22 with the integral collar 23 adapted to bear against the inner face 24 of the roller within the flange 21. The keyway 25 engages the lugs 26 100 on the shafts 9—10—11 of the ink rolls and revolves therewith.

The opposite end of the sleeve is threaded at 27 to receive the threaded cone 28, having the knurled portion 29 to facilitate manual adjustment of the cone. The adjusted position of the cone is fixed by the set screw 30, bearing against the follower 31 engaging the threads 27. This follower may be of a suitable bland metal that 105 will not injure the threads. 110

Advancing or retracting the cone 28 on the sleeve 22 causes it to rise or descend the incline of the taper 20. The height of the cone above the tracks 1 determines the axis of rotation, 5 regardless of the true axis of the roller 18. The symmetrical contact between the cone 28 and the taper 20 is of such area that there is no bucking tendency in the roller 18 in its travel on the tracks 1—3. It is advisable therefore to keep the 10 diameters of the cone and roller as nearly equal as may be. The rolling contact between these two parts reduces the friction to the minimum. It is manifest that the center opening 19 could be counter tapered at 24 and opposed cones used, 15 without departing from the spirit of this invention.

Having thus described this invention what is claimed and desired to secure by Letters Patent is.

1. In combination with an inking roller; an 20 annular traction roller having one side thereof tapered toward its central opening; a sleeve

splined to the shaft of said inking roller and extending through the said opening and having a collar engaging the side of said traction roller opposite from said taper; a conical bearing axially threaded on said sleeve and engaging said taper; and a setscrew extending radially through said bearing and impinging on said sleeve. 80

2. In combination with an inking roller; an annular traction roller having one side thereof tapered toward its central opening and a laterally extending flange on the opposite side thereof; a sleeve splined to the shaft of said inking roller, extending through said opening, and having a collar impinging on the side of the roller opposite said taper and overhung by said flange; a conical bearing axially threaded on said sleeve and engaging said taper; a setscrew extending radially through said bearing; and a follower of soft metal interposed between said setscrew and the threads of said sleeve. 85
